UNITED STATES PATENT OFFICE.

HUBERT JOSEPH STRATEN, OF JERSEY CITY, NEW JERSEY, ASSIGNOR TO ERWIN STEINBACK, OF NEW YORK, N. Y.

APPAREL-COLLAR.

SPECIFICATION forming part of Letters Patent No. 660,344, dated October 23, 1900.

Application filed May 19, 1900. Serial No. 17,283. (No model.)

To all whom it may concern:

Be it known that I, HUBERT JOSEPH STRATEN, a citizen of the United States, residing in Jersey City, in the county of Hudson and 5 State of New Jersey, have invented certain new and useful Improvements in Collars for Clergymen, of which the following is a specification.

This invention relates to an improved collar of that class which are worn by clergymen in connection with a bosom-scarf or rabbis, said collar having the appearance of an ordinary collar without being turned over, whereby a more durable, better-fitting, and better-looking collar is obtained. The turned-over collars heretofore used by clergymen were difficult to iron, did not fit well over the scarf or other bosom covering or garment to which they were secured, and were soon worn out owing to the sharp bending at the turned-over edge, which caused the collar to break at the edge. All these objections are avoided by my improved collar, which consists of a neckband and a main band, both bands being free 15 from each other at their lower edges and provided with turned-over upper edges placed adjacent to each other, a line of stitches connecting said turned-over edges, a line of stitches passing through the bodies of the 20 neckband and main band and said turned-over edges, both of said lines of stitches being continued from the upper edge down each end of the collar to the lower edge of the same, front and side buttonholes in the neckband, 25 and buttonholes at the ends of the neck and main bands, the edges of said end buttonholes being connected by stitches passing through both bands, said bands being separable up to said buttonholes.

40 In the accompanying drawings, Figure 1 represents a perspective view of my improved collar. Fig. 2 is a view, partly in vertical section, on line 2 2, Fig. 1, of one end of the collar; and Fig. 3 is a vertical section on line 3 3, Fig. 2.

45 Similar letters of reference indicate corresponding parts.

Referring to the drawings, A represents the neckband of my improved collar for clergymen, and B the main band of the same. The neckband is doubled, so as to be of two-ply

thickness, and finished by a line of stitches a at the lower edge and turned over at its upper edge. The neckband is provided at the front, sides, and rear ends with buttonholes b, c, and 55 d, so as to be conveniently attached to the neckband of the bosom-scarf or shirt in the usual manner, and applied to the coat-neckband by its overlapping ends. The main band B is composed of two layers—an exterior 60 layer b' of linen and an interior layer b² of muslin—which are doubled over so as to form a four-ply band, which is finished by a line of stitches c' at the lower end and bent over at the upper end. The bent-over ends of the 65 main band and neckband are placed adjacent to each other and connected by a line of stitches d', after which the neckband and main band are each bent over into their normal shape and connected through their 70 inwardly-turned upper ends by a second line of stitches d², that passes through the bodies as well as the inwardly-folded upper edges of the neckband and main band, as shown in Fig. 2. The collar is then starched and ironed 75 in the usual manner. The line of stitches d² is continued at its ends, so as to connect the main and neck bands at their ends. The bands A and B are furthermore connected by the binding-stitches of the rear buttonholes d, so 80 that they cannot become separated and flattened out in washing, but remain folded together, so that no turning over of the collar is necessary when ironing the same. The buttonholes d are closer to the lower edge of 85 the neckband than the remaining buttonholes and pass through both bands, while the buttonholes b and c pass through the neckband only.

The collar can be conveniently made up in 90 any desired height and forms a very comfortable collar, fitting closely to the rabbis and easily attached thereto. It can be easily ironed, and by reason of its non-liability to break at the edge will outlast a number of 95 the old-style collars.

Having thus described my invention, I claim as new and desire to secure by Letters Patent—

A collar for clergymen, consisting of a neckband and a main band, both bands being free 100 from each other at their lower edges and pro-

vided with turned-over upper edges placed adjacent to each other, a line of stitches connecting said turned-over edges, a line of stitches passing through the bodies of the neckband and main band and said turned-over edges, both of said lines of stitches being continued from the upper edge down each end of the collar to the lower edge of the same, front and side buttonholes in the neckband, and buttonholes at the ends of the neck and main bands, the edges of said end buttonholes

being connected by stitches passing through both bands, said bands being separable up to said buttonholes, substantially as set forth.

In testimony that I claim the foregoing as my invention I have signed my name in presence of two subscribing witnesses.

HUBERT JOSEPH STRATEN.
